GEOMETRICAL PUZZLE GAME

Arthur Wormser, Tucson, Ariz.

Application December 11, 1951, Serial No. 261,081

2 Claims. (Cl. 273—157)

My invention relates to geometrical puzzles of a type comprising a number of flat pieces or tiles, all or only a portion of which are adapted to be assembled to form various figures, in particular to form repetitions of the same shape with different arrangements.

Geometrical puzzles as a class are exceedingly old, but all of them heretofore produced have had one or more undesirable characteristics from the standpoint of exciting interest or sustaining interest in different classes of people. More specifically, when prior known puzzles comprised pieces of such geometrical character that forming desired figures was easy, the number and variety of possible figures were limited and interest quickly lagged. Such puzzles would normally be for children, and adults would have only passing interest in them. By increasing the number of pieces in puzzle sets of the type discussed, as, for example, by multiplying the total number of pieces by two or more, the number and variety of possible figures were increased; but solution of problems became much more difficult, and yet what resulted were platitudes from a geometric point of view, offering no surprising constellations. Moreover, a puzzle in which all pieces of a given shape, or a relatively large number of them, occur more than once is limited in the number of different sub-symmetries and figures from partial sets which may be made.

The principal object of my invention is the provision of a new and improved geometrical puzzle.

Another object of my invention is the provision of a geometrical puzzle which will be of interest to both children and adults.

Another object is a geometrical puzzle which may be played in many different ways, and in a manner to solve different types of problems.

A further object of my invention is to shape the pieces of a geometrical puzzle in such a manner that a small number of pieces will produce a great variety of figures, and particularly figures of greatly varying angles showing in their outlines.

A still further object is a geometrical puzzle which presents, in its solutions, sufficient difficulty to stimulate interest but not enough to create discouragement.

Yet a further object is to provide a geometrical puzzle from which innumerable basic symmetrical figures may be made, using either the full set or a part of it.

I have illustrated my invention by showing several different embodiments thereof, with illustrative figures made from the set of each embodiment. By particular reference to the main embodiment, I have further illustrated the richness of the game and features having significance in playing it.

In the drawings:

Fig. 1 is a plan view of a preferred embodiment;

Figs. 2 to 4, inclusive, show symmetrical figures which can be made with the whole set of Fig. 1;

Figs. 5 to 7, inclusive, illustrate figures made with part of the set;

2

Figs. 8 and 9 are whole-set figures using the same sub-symmetries found in Fig. 2;

Figs. 10 to 13, inclusive, show additional part-set figures;

5 Figs. 14 and 15 illustrate a type of figure which I call magic block;

Fig. 16 is a square made of the same tiles as Fig. 1, but built up differently;

10 Fig. 17 shows four different solutions for the same shape figure;

Figure 18 illustrates how two elements form the tiles of Fig. 1;

Figs. 19 and 20 show two asymmetrical pictures formed with the Fig. 1 set;

Fig. 21 is a plan view of another embodiment of the invention;

Figs. 22 and 23 illustrate figures formed with the Fig. 21 set;

Fig. 24 shows still another embodiment;

Figs. 25 to 27, inclusive, are illustrative figures made with the Fig. 24 set; and

Fig. 28 shows a fourth illustrative embodiment of the invention.

Referring now first to Fig. 1, a preferred embodiment 25 of my invention, the puzzle there shown comprises ten flat pieces or tiles 10 to 18 inclusive, there being two tiles 14, all of the others being of different shape. The separate tiles may be made of any suitable material such as heavy cardboard, wood, plastic, ceramic, or the like, 30 of suitable thickness; but the drawings, for convenience, show only their top faces. This puzzle comprises three isosceles triangles 11, 16, and 18; three scalene triangles 12, 14 and 17; three irregular quadrangles 10, 13, and 15; and one irregular pentagon 17. Later in the description I shall refer to couples of twins, but at this point I wish to note that pieces 12 and 13 together correspond to piece 10; pieces 15 and 16 together to piece 17; and the two pieces 14 to one another. Couples in such symmetrical positions are called teamed couples.

40 The corners of all the tiles are located in the intersections of a line system, shown in dotted lines in Fig. 1, consisting of equally-spaced lines drawn at right angles to each other and, therefore, forming identical small squares. I call such a line system a net of squares; the

45 corners of the squares I call intersections; and the sides of the squares, segments. The lines themselves I call division or net lines. It may then be said that in Fig. 1 all the edges of the tiles coincide either with the net lines or with diagonal lines connecting certain intersections. I define the kind of such diagonals by the ratio

50 of the numbers of segments counted in one direction and in a direction perpendicular to it when moving from one intersection on the diagonal to another. Thus in Fig. 1, two kinds of diagonals are to be found; namely 1:1 and 2:1 diagonals. Both kinds are used in tiles 10, 14, 55 15 and 17; the other tiles have only one kind of diagonal.

My invention, as disclosed in Fig. 1 and other figures of the drawings, is based on the discovery that geometric puzzles are rich in possibility of stimulating manipulation 60 and therefore are of lasting interest, if certain fundamental features exist. On the one hand, the pieces must be very irregular; in fact, they should at first glance look as though no principle underlay their shape. On the other hand, a small number of such seemingly irregular and unrelated pieces should produce a large number of constellations resulting in a great variety of symmetrical figures. Finally, the outlines of the figures should show a great variety of angles in order to vary the general looks considerably.

70 I have further discovered that, although the last mentioned feature may be fulfilled by angles as they occur in regular polygons, such angles normally limit very greatly

the second feature (i.e., the number of figures, particularly symmetrical ones, which can be made). Both features simultaneously are only to be expected, if angles are produced by diagonal lines connecting the intersections of a net of squares as defined above. The non-diagonal sides of the tiles, accordingly, will comprise one or more segments of the net lines. This is true in all puzzles according to my invention.

Following the features discussed above, I have further discovered that a small number of pieces are effective to form a large number of interesting constellations if certain additional characteristics are maintained. These characteristics, all of which need not be present at the same time however, are: (a) not more than two shapes repeat; (b) no repeating shapes occur more than twice; (c) preferably no pieces are geometrically regular and very few, and not more than one-third, are symmetrical; (d) not less than two nor more than three different kinds of diagonals are used; (e) the diagonals span no more than four segments in either direction between consecutive intersections; and (f) the maximum length and area of any piece be kept comparatively small.

In Fig. 1, for instance, I draw the outline of the entire set in a net of squares so that the four corners are at intersections four segments apart. Then I subdivide the square outline into individual pieces such that only a single shape, 14, repeats once, and only the two kinds of diagonals mentioned above are used. Only three pieces 11, 16 and 18 are symmetrical, and all pieces are irregular polygons. The largest tiles, 10 and 17, have an area of $\frac{5}{32}$ of the entire set and the longest tiles, 14, are $\frac{3}{4}$ of the length of the whole set.

The number of possible figures which can be made with the entire set or with parts of the set of Fig. 1 is incalculable. They are interesting from various points of view. Reference will first be made to Figs. 2 to 4, inclusive, which are made with all ten tiles.

Figs. 2 and 3 are what I call Y-symmetries or Y-symmetrical figures, because they have two identical shapes on either side of a center line arranged mirror-like as in the letter Y. In the case of Fig. 2, the center line is a joint along which the two identical parts may be split. As mentioned above, a couple of twins in such a position is called a teamed couple. Fig. 3 on the other hand cannot be split completely along a center line, although its outline is also Y-symmetrical. I call such symmetrical figures blocks.

A closer inspection shows that in Fig. 2 each of the twins $10+12+13+14+16+18=11+14+15+17$ can be split into smaller couples $14=14$, $17=12+13$, and $11+15=10+16+18$. These couples are teamed with the same center line as the whole figure, and therefore form sub-symmetries of the complete figure. In Fig. 3 sub-symmetries are also found. The single tile 11 is one, which in this case is not a team but a block. The tiles $14=14$, $15+18=10+16$, and $17=12+13$ are teamed couples, however.

A symmetry without sub-symmetries may be called a basic symmetry; and it is a surprising fact characteristic of the puzzles of my present invention that innumerable basic symmetries can be formed, both with the entire set of tiles and with a part of them. In Fig. 4 no sub-symmetry is found and it is, therefore, a basic symmetry.

It is worth mentioning that Fig. 4 is Y-symmetrical both about a vertical and a horizontal axis; and it is also symmetrical about its center in such a way that any straight line drawn through its center will divide it into two identical halves which, however, are not arranged mirror-like. I call this an X-symmetry because the letter X has this type of symmetry. A figure which is not Y-symmetrical but is symmetrical about its center I call Z-symmetrical as in that letter. An example of a Z-symmetry will be pointed out by reference to other figures.

A constellation consisting of a teamed couple is not

basic, because the teaming can be done with the twins in a variety of positions with relation to a center line, a center, or a block which serves as a nucleus. The couples themselves, however, may be basic or not. Both basic and composite couples were pointed out in Figure 2. The combinations $14+15+11=14+10+16+18$ in Fig. 2 and $14+15+18=14+10+16$ in Fig. 3 are composite couples because they can be further split into teamed couples such as $15+11=10+16+18$ in Fig. 2. Couple $17=12+13$ in both Figs. 2 and 3, on the contrary, is basic. Tile 11 in Fig. 3 is a basic block, while the whole Fig. 3 is a composite block.

Basic symmetries are interesting, especially when they are produced with seemingly as arbitrarily-shaped tiles as those of Fig. 1. If, for example, the tiles 10, 11, 12, 13, 14 and 15 were taken, one would think of a number of symmetrical figures composed of the sub-symmetries 11 , $14=14$ and $10=12+13$ as they occur in Fig. 1. It seems impossible to avoid sub-symmetries; yet there are many ways of arranging these tiles without sub-symmetries, as shown by the illustrative arrangements of Figs. 5 to 7, inclusive. Fig. 5 shows three basic couples having no similarity to any arrangement found in Fig. 1. Fig. 6 shows less than half of the basic Y-blocks possible; and Fig. 7 shows two examples of Z-blocks, as mentioned hereinabove. As explained herein below, basic symmetries are innumerable in the puzzle according to Fig. 1.

As interesting as the task of finding basic figures are their applications as sub-symmetries. For in every figure that is not a basic symmetry, its basic sub-symmetries may be re-arranged or re-shuffled with all basic blocks and couples left undisturbed. This manipulation produces many new and unexpected shapes. Figs. 8 and 9 show two examples of the innumerable possible results of re-shuffling the sub-symmetries of Fig. 2. On first inspection these two figures appear to have no similarity to Fig. 2; they are so distinct in outline. Closer study will show, however, that the basic couples $14=14$, $15+11=10+16+18$, and $17=12+13$ have merely been re-shuffled.

Of course, the greater the variety of basic figures as to tile combinations and outline, the greater the variety of shapes of figures resulting from re-shuffling. With the ten tiles of Fig. 1 and only two alike, there are 768 different combinations of tiles which may be selected, including the entire set. Although half of these combinations will not form basic symmetries, the number of basic figures is tremendous because many combinations form numerous or even innumerable basic symmetries. On the average, combinations with a large number of tiles form more basic figures than combinations with a smaller number; but even the small combination of $10+15+16+18$ which forms a couple in Fig. 3 forms a second couple as shown in Fig. 10, an X-symmetry in Fig. 11, and three Y-symmetries as shown in Fig. 12. No basic Z-symmetry happens to be formed by this combination; but Fig. 13 shows three composite Z-symmetries based upon the couples appearing in Figs. 3 and 10.

I referred hereinabove to the great variety of angles which may be formed in the outline of figures made according to my invention. For the puzzle of Fig. 1, Figs. 2, 3, 4, and 9 may be referred to to explain the features of this particular characteristic. Angles are formed because of the existence of the diagonals; but the tiles may be arranged in such a way that all or some of the diagonals are hidden in the body of the figure in such a way that their angle-forming function is lost. Obviously, all diagonals are concealed in Fig. 1, and only the four right angles at the corners show. This hiding may apply to either or both types of angles found in Fig. 1, whereby I make the same distinction between

various kinds of angles as between the kinds of diagonals producing them.

The outline of Fig. 2, for instance, shows both 1:1 and 2:1 angles, while Fig. 4 shows only 1:1 angles. A great variety of angles is caused to appear by the fact that a 1:1 diagonal and a 2:1 diagonal will produce a 3:1 angle. Such an occurrence may be seen in the outline of Fig. 2 between tiles 15 and 17. The same 3:1 angles may be observed by noting the angle which tiles 10, 14 and 15 make in Fig. 1 at their common vertex. A by far greater variety of angles results if the net of squares is not left intact. The net is unbroken or plain in Fig. 2, but it is broken in Figs. 3 and 9. The angle formed between tiles 15 and 17 in Fig. 3 is a 7:1 angle. Many more kinds of angles result if more than one broken net occurs in a single figure. Note, for example, the approximation of two arcs at the top of Fig. 9.

Broken net lines make the solution of puzzles harder in a way; but they also help by indicating what tiles are used and where sub-symmetries exist. A broken net irrevocably divides a symmetrical figure into sub-symmetries; and these can be solved easier than the whole figure. One of the most surprising facts about the puzzle in Fig. 1 is that basic symmetries can be formed with broken net lines, using all or part of the set. I shall call these figures magic blocks.

Fig. 14 is an example of such a magic block and also illustrates the geometric fact which makes this type of figures possible. Using the net lines of Fig. 1, four 2:1 diagonals can be drawn in such a manner as to form a square whose sides do not coincide with any net lines. Such a square cannot be made with the puzzle of Fig. 1. But tiles can be arranged to fill such a suggested square completely, with certain parts projecting beyond it. In Fig. 14 I show such an arrangement with three sides of the square formed by the sides of tiles and the remaining side indicated by the dotted line, thus forming what may be called a virtual square with certain parts projecting from one side of it. The projecting portion is so shaped, however, that its outline can be matched by one of the remaining tiles, 14.

Magic blocks may be of different types, for either two or three sides of the virtual square may be formed by actual joints with the remaining one or two sides virtual like the dotted line in Fig. 14; and such virtual sides of the square, as they may be called, can occur at adjacent or opposite sides. In addition to that, a virtual rectangle equal to two adjacent virtual squares, as shown in Fig. 15, produces a special class of unusual magic blocks. Several hundred of such magic blocks exist.

Another feature of my invention illustrative of its unusual richness has to do with the large number of different ways in which many figures may be formed. I have mentioned that in broken-net figures the shapes of their sub-symmetries are unalterable. As would be expected, such figures have comparatively few solutions. Plain- or unbroken-net figures offer more solutions, in general; and the simpler the figure, the greater the number of solutions which may be expected. I have recorded 1,632 different arrangements of tiles to form a square according to Fig. 1, including different angular positions and mirror image positions. These arrangements may be classified into 204 different types, of which 23 have no sub-symmetries of any kind. Some of them, of which Fig. 16 is illustrative, have all the five sub-symmetries possible in a square; viz, Y-symmetry about vertical and horizontal axes, Y-symmetry about either of their two diagonals, and Z-symmetry.

Another illustration of multiple solutions is indicated in Fig. 17. There are many ways of forming such a trapezoid, but I show only four solutions, each quite different from the others. Solution A is a team formed of a single basic couple joined at the vertical center line. Solution B consists of the couple 14=14 and two

basic blocks, 13+16 and 10+11+12+15+17+18. Solution C consists of the couple 17=12+13 and the basic blocks 18 and 10+11+14+14+15+16. Solution D is a basic block with no sub-symmetries.

Fig. 17 is used to illustrate still another feature of my invention. Fig. 17A shows no net lines, and the reference characters are not applied to the tiles. This represents a condition in which the tiles have no markings of any kind. In this condition the puzzle is hardest in making any solution. Fig. 17B shows only reference characters; Fig. 17C, net lines only; and Fig. 17D, both net lines and reference characters. The markings are placed on both sides of the tiles, and usually I employ letters instead of numerals to identify individual tiles. The easiest set to solve all kinds of puzzles is the one which has both net lines and symbols identifying the pieces.

One reason why the puzzle of Fig. 1 offers such a variety of combinations is the fact that the pieces, while irregular and seemingly entirely unrelated, are actually built up of only two elements or basic shapes repeated again and again. This build-up from elements becomes particularly rich if one or more of the elements occurs as a complete tile. If only a few elements, preferably at least two and not more than three, are used in the build-up and other features of my invention are observed, a puzzle results which is rich and stimulating but not so difficult as to create discouragement. Fig. 18 illustrates this feature as present in the puzzle of Fig. 1. The tiles are in the same order as in Fig. 1, but separated from one another. The broken lines separate the pieces into their constituent elements 12 and 16, these elements being identified by the characters 12' and 16' respectively. It will be noted that each of the elements forming the tiles occurs as an individual tile, and that the apparently arbitrary shapes in reality form all possible combinations of one to three elements 16', one to two elements 12', and one element 12' with one to three elements 16', except that combination of two elements 12' which would extend over four net squares and be objectionable for that reason.

Figs. 19 and 20 show two illustrative asymmetrical figures made with the entire set of tiles of Fig. 1. The features discussed in connection with the illustration of symmetrical figures are shown to be of significance in the formation of such picture figures. In the formation of such figures, advantage is taken of the individualistic characteristics of the tiles, such as the head of the dancing man in Fig. 20; and the muzzle, tail and forefeet of the sitting dog of Fig. 19. If these portions of the figures had to be made up of multiple pieces of similar shape, the problem of formation would be greatly increased. All kinds of objects can be simulated closer than with other geometrical puzzles; in fact, it is comparatively easy to form persons, animals, tools, ornaments, letters of the alphabet, etc. and even to produce different attitudes and styles for the representation of the same object, according to the plain or broken nets being applied.

Many other specific geometrical puzzles may be produced, following the principles of my invention. Each such puzzle has to a greater or lesser extent the characteristics, richness, and possibilities of puzzle problem solution discussed in connection with Fig. 1. Each specific puzzle, however, has peculiarities of its own, as will be observed by playing with it. In general, failure to include one or the other of the specific features discussed decreases the richness of any puzzle made according to my invention; but sometimes richness may be sacrificed to advantage when some other interesting characteristic is present instead. It is obviously impossible to disclose every specific form which the puzzle of my invention may take, and I shall therefore confine my disclosure to illustrative modifications.

Fig. 21 is an eight-tile puzzle, and Figs. 22 and 23

are illustrative figures made therefrom. The tiles, numbered 19 to 24 inclusive, have different shapes except that there are two tiles each of shapes 21 and 23. This puzzle incorporates the most significant features of my invention, but tiles 20 and 23 extend over all four segments into which the puzzle may be divided; and the puzzle will be expected to be limited slightly, as contrasted with Fig. 1, for this reason. Tile 21 of Fig. 21 is the same as tile 12 of Fig. 1; but there is no tile corresponding to tile 16. All of the tiles of Fig. 21, except tiles 20 and 24, can be divided into elements or sections corresponding to tile 12 of Fig. 1; while the two exceptions contain another element. Therefore, two basic elements enter into the formation of the tiles of this modification, the same number as in Fig. 1. This modification of the invention, while less rich in some respects than the puzzle of Fig. 1, is very rich as contrasted with puzzles of the prior art. The illustrative Figures 22 and 23 are a very smooth and very complicated figure, respectively, but both are symmetrical and harmonious.

In the modification just discussed, the diagonals are of the same kind as one of the two kinds used in Fig. 1, and the net of squares consists of 4 x 4 small squares as in that first embodiment. It is by no means necessary that this arrangement be followed, however. In Fig. 24 it is necessary to use twelve small squares in the vertical and fifteen squares in the horizontal direction to draw the diagonal lines needed for the formation of all the tiles in this puzzle. Of the ten tiles numbered 25 to 32 inclusive, only tiles 25 and 26 are duplicated, all are geometrically irregular, and only tile 30 is symmetrical. While the diagonals are drawn in twelve by fifteen squares, the two encircled points at the common vertices of tiles 28 and 30 do not lie on the intersection of twelve by fifteen net lines; but they do lie on intersections of a line system forming sixty by seventy-five squares. This game is even richer in possibility of figure formation than Fig. 1 in that the sides are measured in smaller units and therefore furnish a greater variety of matching lengths. One feature tending to make it less rich than the Fig. 1 puzzle is the greater number of kinds of diagonals. It does not have 1:1 diagonals but does have 2:1, 3:1 and 4:3 diagonals. Also, it cannot make a whole-set square. Its most pronounced characteristic from a geometric point of view is that it furnishes ever more surprising combinations, geometrically speaking, than Fig. 1. Figs. 25 to 27 serve to illustrate this fact. In Fig. 25 two identical center blocks form a rectangle, and a teamed couple completes the figure. In Figs. 26 and 27 not only the symmetrical tile 30 forms a sub-symmetry, but both have a number of other sub-symmetries.

While most of the puzzles of my invention will form a square or rectangle and may to advantage be formed originally by dividing up one of these shapes drawn into the net of squares, they may be derived from many other shapes. In Fig. 28 I show a puzzle in the form of a pentagon which embodies all of the features of my invention, including the arrangement of net lines; but this puzzle will not form a square with all of its pieces. The individual tiles numbered 33 to 38 inclusive nevertheless are the same in appearance and outline as some of the tiles of the first described embodiment.

Puzzles according to my invention may be played in many ways, both by a single player and by a group. The winner may be the person who solves a problem first, who solves it in the most original or unique way, or the like. In a group, the better players may be handicapped by being furnished a more difficult set, such as one with no net lines, as explained in connection with Fig. 17. Samples for different problems may be shown by re-reference to Fig. 1.

One class of problems concerns the squares, and the simplest of such problems is to form a square as such, or a square with a given number of tiles. A refinement may consist of establishing certain requirements, e.g.,

that the square have no sub-symmetries, that it have sub-symmetries about a given line such as a diagonal, that it be a Z-symmetry, or that it have as many sub-symmetries as possible. Another requirement offering an inexhaustible number of individual puzzles is that certain tiles be in certain positions. Still another group of puzzles results if certain close relationships between different squares are stated and the problem is to go from one given square to another in the shortest way, using only steps according to the stated relationships. The last two groups of puzzles have the feature, proper for a puzzle, that sometimes there may be no solution at all for a given problem.

Another class of puzzles is to take only a certain number of tiles and attempt to form specified "basic figures" such as basic blocks, basic couples, and X-symmetries, however built. Of the possible 768 combinations of tiles, one-half will never form basic figures, as has been mentioned above. Half of the remaining 384, or 192, are at best apt to form Y-symmetries and those only with the net of squares at a 1:1 angle with the center line, as in Fig. 4. The remaining 192 are basically adapted to form X-, Y-, or Z-symmetries; but even of these, 33 cannot form any couples. The numbers given are based on the shapes and areas of the tiles, and particularly on the fact that all tiles can be considered as comprising combinations of elements shaped like tiles 12 and/or 16 as discussed in connection with Fig. 18. The numbers represent only possibilities; individual combinations may lack one or more symmetry, or be entirely barren. On the other hand, certain combinations (and particularly those with a relatively large number of tiles) may form hundreds of basic figures, some of them connected by relationships similar to yet different from those existing between squares. These figures may serve as an indication of the very large number of real puzzles embodied in the game of basic figures. The fact that every so often one may run into an insoluble problem makes the game really puzzling.

Still a further group of puzzles is concerned with the re-shuffling or re-grouping of given sub-symmetries, one sub-class of which is the formation of families of teams. As discussed in connection with Figs. 8 and 9, this class of puzzles leaves the sub-symmetries intact but arranges them in all conceivable ways, with both plain and broken nets. Played in this way, the game results in the formation of surprising shapes and particularly all kinds of angles, almost without effort on the part of the player. Particular requirements may be, for example, to shape figures with a maximum or minimum number of sides, with only certain angles showing in the outline, etc.

A very interesting and stimulating undertaking is to form pictures of given objects such as a person in a given attitude, a flying bird, a letter of the alphabet, or whatever one may think of. Possibilities of figure formation in this manner are almost unlimited except by the imagination of the player.

I have described my invention and several embodiments thereof in detail, and explained several ways in which it may be used in different kinds of puzzle games, so that those skilled in the art will have a full and complete understanding thereof, but the scope of the invention is defined in the claims.

I claim:

1. A geometrical puzzle consisting of ten tiles together forming a square, said ten tiles being shaped and proportioned in the following manner when said square is divided into sixteen equal unit squares: one quadrangle having one side coincident with the side of one unit square, one side coincident with sides of two unit squares, one diagonal running across one unit square in one direction and two unit squares in another direction, and one diagonal running from corner to corner of one unit square; one isosceles triangle having a base coincident

with sides of two unit squares, and two diagonals each extending across one unit square in one direction and two unit squares in another direction; one scalene triangle having one side coincident with a side of one unit square, one side coincident with sides of two unit squares, and a diagonal extending across one unit square in one direction and two unit squares in another direction; one quadrangle having two sides coincident with one side of a unit square, one side coincident with sides of two unit squares, and one diagonal extending from corner to corner of one unit square; two scalene triangles, each having a base extending along the sides of three unit squares, one diagonal side extending across one unit square in each direction, and one extending across two unit squares in one direction and one unit square in another direction; one quadrangle having one side coincident with a side of one unit square, one diagonal side extending across two unit squares in one direction and one unit square in another direction, and two diagonal sides extending across one unit square in each direction; one isosceles triangle having two equal sides coincident with sides of a unit square and a base as a diagonal from corner to corner of such unit square; a pentagon having two sides coincident with sides of a unit square, a third side forming a diagonal across two unit squares in one direction and one unit square in another direction, a fourth side coincident with a side of another unit square, and a fifth side extending diagonally from corner to cor-

ner of one unit square; and an isosceles triangle having a base coincident with sides of two unit squares, and two equal sides forming diagonals from corner to corner of separate contiguous unit squares.

- 5 2. A geometrical puzzle consisting of ten tiles, none of the shapes of which tiles occurs more than twice and of which no more than two are duplicated, said ten tiles comprising six triangles, three irregular quadrangles, and one irregular pentagon, one of said triangles being a relatively small isosceles triangle and another of said triangles being a relatively small right-angular scalene triangle, the remaining tiles being larger than said isosceles and scalene triangles and formed of a combination of two or more of said small triangles of the same shape or two or more of said small triangles of different shapes.
